LUBRICATING APPARATUS.

1,074,730.

Specification of Letters Patent.

Patented Oct. 7, 1913.

Application filed August 5, 1905. Serial No. 272,822.

To all whom it may concern:

Be it known that I, WILLIAM L. MORRIS, a citizen of the United States, and resident of Cleveland, county of Cuyahoga, and State of Ohio, have invented a new and useful Improvement in Lubricating Apparatus, of which the following is a specification, the principle of the invention being herein explained and the best mode in which I have 10 contemplated applying that principle, so as to distinguish it from other inventions.

My invention relates to a system for supplying lubricating oil, for the various purposes to which such oil is put, at a number 15 of different points in a machine or in any number of machines throughout a shop or power station.

The object of the invention is to provide means for effecting the above purpose that 20 will be efficient, economical and continuous in their operation.

To the accomplishment of these ends my system provides not merely for the distribution of the oil to the points desired, but, 25 since for many purposes it is desirable to use oil in excess quantity, for the collection of such excess, or "drips," and for freeing the same from impurities and returning them to the general system to be used over 30 again.

My system further includes means whereby any part thereof may be temporarily cut off from the remainder to be cleaned or repaired without interrupting the operation 35 of the system as a whole.

My invention consists finally of the combination, arrangement and construction of the various mechanisms and devices herein-after fully described and specifically set 40 forth in the claims.

The annexed drawing and the following description set forth in detail certain mechanism embodying the invention, such disclosed means constituting but one of various mechanical forms in which the principle 45 of the invention may be used.

In said annexed drawing: Figure 1 represents diagrammatically an approved form of arrangement of the various parts of my lubricating system, such parts being shown therein in vertical cross-section. Fig. 2 is a horizontal sectional view taken on an imaginary plane cutting the points of the arrows 2-2 through the drip collecting trap F* of

Fig. 1. Fig. 3 represents a vertical cross- 55 section of an oil-cup suitable for use in connection with my improved lubricating system. Fig. 4 represents upon an enlarged scale the "spreader" which forms a feature of the distributing tanks B¹, B². Fig. 5 60 represents, also upon an enlarged scale, a "sight-feed" placed in the overflow-pipe leading from said distributing-tank; and Fig. 6 represents, in enlarged horizontal 65 cross-section, an improved form of union connection designed for use in my lubricating system.

It is quite generally acknowledged that oil retains indefinitely its lubricating properties and hence that, when freed from the 70 impurities taken up in the course of its use, it can be used over and over again. These impurities are of two distinct classes, one consisting of particles of grit, metal, and carbonated fats, all of which are insoluble 75 but readily carried in suspension, the other consisting of water in the form of infinitely small drops so thoroughly mingled with the oil as to form an emulsion therewith. Accordingly, as will appear, my lubricating 80 system includes means for removing both of these classes of impurities from the oil.

As shown in the arrangement of parts diagrammatically illustrated in Fig. 1, my system comprises a receiving reservoir A, a distributing reservoir B, pumping mechanism D with pipes for transferring oil from such receiving reservoir to such distributing reservoir, oil distributing pipes E leading from the distributing reservoir B to the points to 90 be lubricated, drip-collecting pipes F leading from such points to receiving reservoir A, and oil purifying means interposed in such drip-collecting pipes, comprising a water separating device M, a vaporizer N, 95 and a clarifier P.

Receiving reservoir A would ordinarily be in the basement of the shop or factory where sufficient room may be had to locate in close proximity thereto the oil-purifying 100 devices as shown, and also where sufficient fall may be had between it and the machines where the oil is used to cause the drips from such machines to return to it by force of gravity alone. The initial supply 105 of oil for use in the system, as well as such additions thereto as may from time to time be required, may be placed in this reservoir.

The distributing reservoir B is preferably sufficiently elevated to cause the oil to flow therefrom to all parts of the system under force of gravity alone. However, as will appear, it may be readily adapted to distribute the oil under air pressure where this method is found desirable. This reservoir is designed to serve both as the distributing center of the system and, since the oil while contained therein is in a more or less quiescent state, as a precipitation chamber wherein the finer impurities in the oil are allowed to separate out. In order to utilize fully this use of such reservoir I make it consist of two or more separate receptacles or tanks B¹ B², and am thus able to allow the contents of the one to remain entirely undisturbed while drawing oil from the other, and so to secure a proportionally more thorough precipitation of the minute particles forming the impurity referred to. Oil is alternately admitted to these receptacles through feed-pipe D¹ and branches d¹ d². Oil is directly withdrawn from either of them for lubricating purposes by means of pipe E which distributes the oil to the desired points about the machine or shop through branches E¹ leading to the oil-cups E², which feed the oil at any desired rate to the various bearings and mechanisms. To draw off from B¹ or B² any surplus of oil, or to return to the receiving reservoir A oil from which the sedimentary impurity has been precipitated, an overflow b is provided. This overflow is preferably in the form of a horizontally-disposed, recurved or circular trough, in order to provide means for quickly withdrawing the oil and to avoid disturbing the sedimentary deposit in the bottom of the receptacles. A pipe b¹ adjustably held in stuffing-box b² permits the raising or lowering of the overflow and serves to conduct the oil to funnel b³ whence it is led through pipe B⁴ and branch B⁵ to receiving tank A. A sight-feed B⁶ shown in enlarged cross-section in Fig. 5, permits a close inspection of the escaping liquid, which can be diverted by means of suitable stop-cocks through branch-pipe B⁷ to an independent receptacle K or through B⁷ to waste-pipe B⁸. Gages b⁴ permit a similar inspection of the contents of receptacles B¹ B².

Instead of lowering the overflow in the manner just described, the same result may be effected by admitting water to the bottom of the tank which will raise the oil to the level of the overflow. To admit water for this purpose, connection is made between the bottoms of the receptacles and water main D² by means of pipe d³ and branches d⁴ d⁵. Spreaders or nozzles d⁶ removably held in the ends of branches d⁴ d⁵ by vertical rods d¹⁰, admit the water somewhat above the bottom of the receptacles and in such man-

ner as to avoid any agitation of the aforesaid sediment.

The cups E² by which the oil is fed from distributing-pipe E to the bearings, etc., may be of any approved pattern. For use in my system, however, especially when employed as a gravity or low pressure feed system, I have devised a special form of oil-cup, shown in detail in Fig. 3. This cup consists essentially of a cup-body e centrally positioned in the bottom of which is the boss e¹⁰ provided with an axial bore, the upper portion of which is shaped to form a valve-seat. The lower end of this boss projects downwardly into the usual sight-feed e⁷, whence the oil is conducted to the bearing through the bore in plug e⁸ which is threaded to be secured on such bearing. A suitable cover e¹ is secured to the top of the cup. Fitted within the cup so as to be vertically reciprocable therein is a piston e⁴ provided on its lower face with a projecting valve e⁶ adapted to close the bore in boss e¹⁰ and in its upper end with a recessed chamber e⁵ from which a port e¹² passes axially through valve e⁶. When the valve e⁶ is in position to close the bore in boss e¹⁰, the piston rests upon a ledge e⁹ formed in the walls of the cup. Oil is admitted to the cup beneath the piston through the bore in the boss e¹¹ to which the distributing-pipe branch E¹ is connected in any suitable manner. The pressure of the oil thus admitted to the cup raises the piston and thereby opens the valve e⁶, permitting the oil to escape to the bearing. The distance the piston may be raised is regulated by means of an adjusting screw e² centrally threaded in cover e¹ and provided with a lock-nut e¹³. The lower end of the screw e² is provided with a disk-like projection e³ which is designed to lie within the recess in chamber e⁵, thereby making possible not only the limitation of the upward movement of the piston but also the securing of the piston so that the valve e⁶ is held permanently open. Obviously such set screw is also adapted to hold the valve permanently closed, and thus forms an independent means of operating the valve. That the reciprocation of the valve-bearing piston may be perfectly free it is purposely fitted within the cup loosely enough to permit a thin film of oil to lie between it and the walls of the cup. Such small quantities of oil as may leak past the piston collect in chamber e⁵ and escape from there through the port in valve e⁶ to the bearing. When the valve is closed tightly by means of its stored weight such leakage is stopped by the piston resting on ledge e⁹ above described. To supply oil to these cups in case of emergency, as when both tanks of reservoir B are out of service, independent or auxiliary distributing tanks T, of which only one is

shown, are connected with each group of such cups. It is particularly with a view to occasions when the supply is being drawn from such auxiliary tank that the valves of the cups are constructed to be held open, for the pressure of oil might not be sufficient in such case to raise the piston in the cup.

The drip collecting means comprise a set 10 of branch pipes F, leading from the several drip-collecting receptacles F¹, F², F³, and connected to discharge their contents through pipe F⁴ directly upon clarifier P or through pipe F⁵ into the water separating device M. Where the excess of oil 15 is from an ordinary bearing and hence practically pure a plain funnel device as shown at F¹ or F² will suffice for a drip receptacle. Where, however, the oil is collected from the cutting tools of a drilling or milling machine, and hence contain metal chips, and the like, or where other gross impurities are apt to become mingled with the oil in connection with its use in a machine, a receptacle 20 of the form shown at F³ is best provided. This receptacle consists of the drip pot f, the opening of which is fitted with a perforated cover f¹, and within which depends the screen basket f². These prevent such grosser impurities from clogging the collecting pipes. Manifold traps F⁴ are provided where convenient in the course of drip-collecting pipes F to separate such of the impurities as escape through the drip-pots. 25 Such trap, Figs. 1 and 2, consists preferably of two members f³ f⁴, the upper of which has a partition f⁵, on one side of which the oil is received and on the other discharged, thus preventing heavy impurities 30 from being borne directly through the trap by the force of the current of oil. To prevent the precipitation of such or similar impurities elsewhere in the line than in such traps, the various pipe connections through- 35 40 45 50 55 60 65 70 75 80 85 90 95 100 105 110 115 120 125 130 cut the system and particularly in the drip-collecting set of pipes are made as smooth internally as possible. To this end I have designed the form of joint shown in Fig. 6. This joint comprises two sleeves h h, respectively threaded on the abutting pipe-ends, and a filling-in ring h¹ of compressible material lying in a groove in each sleeve and between the sleeve and such end of the pipe, which rings after the end of the pipe sections have been secured together are designed to be trimmed down so as to leave the bore of the joint smooth and uninterrupted. The ends of the sleeves are held together by means of the coupling-sleeve h² bearing against a flange h³ on one sleeve h and threaded on the other, whereby the whole connection is joined tightly together. The first of the oil purifying devices interposed in the drip-collecting pipe system is an automatic water separator M designed

to separate out such water of condensation as passes engine valve-rods and mingles with the drips as well as water that may be employed in cleaning out the oil distributing and drip collecting pipe lines. It comprises a tank separated into two compartments by a partition m, such compartments communicating freely at the bottom of the tank. At the start, water is introduced into the tank or else allowed to accumulate until high enough to shut-off such communication. The height of water at any time is indicated by means of a gage m¹. The returning drips collected by pipes F are discharged into the larger of these compartments through small openings m² at a higher level than that ever occupied by the water, the object being to discharge such returning oil in the body of oil already collected and not in the water in the bottom of the tank. The accumulation of oil in the larger compartment will raise the level of the water in the smaller compartment to a height somewhat less than that of such oil. Overflows m³ m⁴ are provided therefore at different levels whereby the oil and water may separately escape. These overflows are of the horizontal trough-like design already described in connection with tanks B¹, B², but differ therefrom in that they are attached to the sides of the tank. By means of these overflows the levels of the separated liquids are maintained constant without danger of a sudden inrush of oil building up a head and so disturbing the arrangement. The water escaping by overflow m⁴ is conducted to the sewer by a pipe m⁵. Cock m⁶ at the bottom is connected to draw off the contents of the tank when it is being cleaned. A pipe M¹ connects the tank directly with the pumping mechanism D, which permits the use of tank M as a receiving reservoir, either auxiliary to reservoir A or independently thereof pending the cleansing of the latter, the separation of water in tank M being temporarily omitted. To get tank M back into service as a water separator, the oil on top of the water in the smaller compartment is diverted through branch m⁷ of overflow pipe m⁵ and saved.

In the normal use of tank M as a water separator the oil escapes by overflow m³, being thence conducted by pipe M¹ to the vaporizer N where all remaining traces of water are designed to be removed. The drips may also be led directly to the vaporizer through pipe F⁶ without passing through water separator M. This vaporizer comprises a tank N divided into a number of compartments and connected with a fan N¹, an exhaust-fan as shown, whereby air, admitted through the opening n, is drawn through and over the oil, the compartments of the tank being arranged to insure a thorough contact of the air current with the oil

passing through the tank. The air is preferably heated to the proper temperature for vaporizing the water with a minimum vaporization of oil by being first led over a 5 coil n^1 of steam pipe. A closed compartment n^2 in the tank, connected with water-main D^2 by pipe N^2 presents a cold surface to the vapor-laden air just after it has passed through and over the oil and condenses the 10 water and such oils as may have been vaporized. To insure the thoroughness of such condensation a jet or spray of water from a pipe n^3 is, in addition, introduced into that part of the chamber where the outlet pipe 15 for the air is located. The condensed vapors with the water from the spray are led by the pipe N^3 to an independent receptacle K^1 . If any oil is carried along with the vaporized water it is here retained and may be re- 20 claimed. After passing through the vaporizer just described, the oil is normally led to the clarifier P , which, in the arrangement of parts shown in the drawing, is situated in the upper part of receiving reservoir A . 25 After passing through clarifier P the oil overflows directly into such receiving reservoir, if valve in pipe p^2 be closed or is conducted to pumping mechanism D if said valved pipe be open. This clarifier prefer- 30 ably comprises a filter p and a series of inclined trays p^1 with corrugated bottoms, the corrugations being transversely disposed relatively to the direction of the tray's inclination. Filter p comprises a metal tray with 35 raised sides and having its bottom pierced by a large number of fine passages. The oil is not forced through this filter P under any greater pressure than that produced by its own head, which will be constant, depending 40 upon the height of the sides of the tray. In case the flow of oil is greater than will normally pass through the passages in its bottom the excess will simply run over its sides to be caught on the trays beneath. This is 45 considered better than forcing the oil through the passages under varying pressures and thereby dislodging at times of such increased head the particles separated out when the flow was normal.

50 Most of the connections of the pumping mechanism have already been indicated. The mechanism comprises a pump D placed inside reservoir A and near its bottom, and a motor D^3 to operate the same. As shown 55 the pump D may be connected to draw oil from either the receiving reservoir A through pipe M^3 , from tank M through pipe M^2 , or from filter device P through funnel p^2 . It also has a fourth connection through 60 pipe D^6 directly with the atmosphere. This last connection is used when it is desired to force the oil through the distributing system under air pressure, the covers of distributing tanks B^1 B^2 in such event being tightly 65 closed, and the air being forced therein

through pipe D^1 just as the oil is when oil is being pumped. Whether gravity or pressure-feed is employed, the motor operating the pump should be controlled to maintain a constant pressure upon the oil discharged 70 from reservoir B . Such control is easily effected by having the piston d^8 of the pump connected with the continuously reciprocating piston-rod d^1 of the motor so as to engage therewith in an upward direction only. 75 Such engagement and consequent actuation of the pump will cease as soon as the pressure in reservoir B or connected pipes becomes great enough to balance a weight D^5 secured to pump piston d^8 . 80 The operation of the several parts having been described in passing, it only remains to indicate the manner in which these parts coöperate in the operation of the system as a whole. To this end the system will be 85 described as when arranged in the manner represented in Fig. 1, the various tanks, valves, etc., being in the conditions there shown. As there shown tank B^1 of the distributing reservoir B has been filled with 90 oil and is temporarily cut off from circulation to permit the impurities therein to precipitate out. Upon such precipitation being complete the pure oil will be withdrawn from the tank and returned to receiving reservoir A , either by lowering overflow b or, preferably, by introducing water 95 through pipe d^4 and spreader d^8 and thereby raising the oil gradually to the overflow as fast as it is carried away by pipe b^1 . 100 Heavier oil that may be mingled with the lighter oil, such lighter oil being assumed to form the bulk of the lubricant used, will have formed a separate stratum near the bottom of tank B^1 and can be diverted 105 through pipe B^6 to receptacle K upon being detected in sight feed B^8 . As soon as in the course of the removal of the contents of tank B^1 , the oil has been all withdrawn and water begins to escape over the overflow it can be similarly diverted through 110 pipe B^7 to the waste. Upon tank B^1 being emptied of oil it is ready for cleaning which is conveniently performed by removing spreader d^8 , and flushing it out with water, 115 the dirty water being drained off through waste pipe B^3 . Pending the precipitation of impurities from the oil in tank B^1 , tank B^2 is, as shown in said Fig. 1, in process of being filled with oil from receiving reservoir 120 A , its capacity being large enough to contain the excess of oil over that in tank B^1 and in circulation in the system. In other words, by the time that the oil in tank B^1 is ready to be withdrawn, reservoir A will 125 have been emptied and can be cleaned preparatory to receiving such pure oil. The oil required by the system in the meantime is supplied from tank B^2 through distributing pipe E , the drips collected by pipes F 130

being returned after passing through such of the purifying devices M, N, and P as is thought desirable, directly to pumping mechanism D. Upon tank B¹ being cleaned and again ready for service, the arrangement just described is reversed; tank B² is cut off from circulation and used as a precipitation receptacle while tank B¹ is employed in the capacity of distributing reservoir. Oil-cups E² having been properly adjusted, their operation is automatic so soon as the supply is turned on from tank B¹ or B². In case a machine is idle the branch pipe E¹ leading to the particular group of cups connected with such machine is cut off. If for any reason both tanks in reservoir B are temporarily out of service the independent distributing-tanks T one of which is designed to be attached to each group of cups, can be employed to supply oil thereto.

When it is desired to clean out the distributing-pipe system, the oil is rapidly flushed through each separate pipe to feed cups E², being thence conducted by the drip-collecting pipes directly through pipe F² to receiving reservoir A. To clean out the latter pipes, the drip-pots are first cleaned out and warm water then passed through them, such oil as may be carried along being separated out in separator M. The manner of disconnecting such separator from the system in order to clean it has already been described. The procedure in cleaning drying device N is similar. To clean the clarifier P its various parts p and p¹ may be removed entirely and washed, the oil in the meantime discharging directly into reservoir A. When reservoir A is being cleaned, tank B is adapted to be temporarily used as a storage reservoir as has been already shown.

To adapt the system to feed oil under air pressure all that is necessary is to secure the caps on tanks B¹ B² so as to make such tanks air-tight. Then forcing oil into such tanks against the volume of air confined therein will compress such air sufficiently to provide the pressure desired. If through leakage or other cause, as a lowering of quantity of oil in the tank, such pressure becomes inadequate, the pump is quickly connected to pump air into the tank to restore the pressure, the maintenance of the pressure being automatically regulated, whether by the introduction of oil or air in the manner already set forth.

It will thus be seen that my system, by its arrangement of parts and structural features, provides for the automatic feeding of oil at any number of points in adjustable quantities, for the thorough removal of all the usual impurities in oil that has been once used for lubricating purposes, and for the return of such purified oil to the general system, alternate connections being provided throughout whereby one portion of the sys-

tem may be cleansed or repaired without interfering with the continuous operation of the system as a whole.

Having thus described my invention in detail, that which I particularly point out and distinctly claim is:—

1. In lubricating apparatus, the combination with oil distributing and drip collecting pipes, of means for circulating oil therethrough and a plurality of settling tanks separately connected with said pipes for receiving a portion of such oil and retaining the same from circulation, said tanks being arranged to permit the discharge of oil from one, and its retention in the other, and vice-versa.

2. In lubricating apparatus, the combination with oil distributing and drip collecting pipes, of means for circulating oil therethrough, a receptacle connected therewith, an overflow for said receptacle, a discharge pipe for said overflow having a plurality of discharge connections, and means adapted to raise the oil in said receptacle up to and over said overflow.

3. In lubricating apparatus, the combination with oil distributing and drip collecting pipes, of means for circulating oil therethrough, a plurality of receptacles independently connected therewith, overflows for said receptacles respectively, and means for raising the oil in each of said receptacles up to and over the corresponding overflow.

4. In lubricating apparatus, the combination with oil distributing and drip collecting pipes, of means for circulating oil therethrough, a plurality of receptacles independently connected therewith, overflows for said receptacles respectively, a discharge pipe for each of said overflows having a plurality of discharge connections, and means for raising the oil in each of said receptacles up to and over the same.

5. In lubricating apparatus, the combination with oil distributing and drip collecting pipes, of means for circulating oil therethrough, a receptacle connected therewith, an overflow for said receptacle, a discharge pipe for said overflow having a plurality of discharge connections, and means adapted to supply to said receptacle a liquid heavier than oil in order to raise the oil therein up to and over said overflow.

6. In lubricating apparatus, the combination with oil distributing and drip collecting pipes, of means for circulating oil therethrough, a receptacle connected therewith, an overflow for said receptacle, and means adapted to supply to said receptacle a liquid heavier than oil for raising the oil therein up to and over said overflow, said means including a spreader.

7. In lubricating apparatus, the combination with oil distributing and drip collect-

ing pipes, of means for circulating oil therethrough, a receptacle connected therewith, an overflow for said receptacle, a discharge pipe for said overflow having a plurality 5 of discharge connections, and means adapted to supply water to said receptacle for raising the oil up to and over said overflow, said means including a spreader.

8. In lubricating apparatus, the combination with oil distributing and drip collecting pipes, of means for circulating oil therethrough, a plurality of receptacles independently connected therewith, overflows for said receptacles respectively, a discharge 10 pipe for each of said overflows having a plurality of discharge connections, and means adapted to supply water to the respective receptacles for raising the oil therein up to and over the corresponding over- 15 flow, said means including a spreader.

9. In a lubricating apparatus, the combination with oil distributing pipes and drip collecting pipes, of an inclosed receptacle connected with said oil distributing pipes, and pumping means adapted optionally to 25 supply either oil or air to said receptacle.

10. In a lubricating apparatus, the combination with oil distributing pipes and drip collecting pipes, of an inclosed receptacle 30 connected with said oil distributing pipes, pumping means adapted optionally to supply oil or air to said receptacle, and means

for regulating the relative amounts of oil or air thus supplied.

11. In lubricating apparatus, the combination with oil distributing pipes and drip collecting pipes, of a receiving reservoir, 35 pumping means for supplying oil therefrom to said oil distributing pipes, and an oil clarifying device, connections being provided whereby said drip collecting pipes discharge optionally into said clarifying device, said receiving reservoir, or said pumping means, and whereby said oil clarifying device discharges optionally into said receiving reservoir or said pumping means.

12. In lubricating apparatus, the combination with oil distributing pipes and drip collecting pipes, of a receiving reservoir, pumping means for supplying oil therefrom to said distributing pipes, and a water separating device, connections being provided 45 whereby said drip collecting pipes discharge optionally into said water separating device or said receiving reservoir, and whereby said water separating device discharges optionally into said receiving reservoir or said pumping means.

Signed by me this 2nd day of August 1905.
